COMPARTMENTED PACKAGING TRAY

James Raymond Loney, Cote St. Luc, Quebec, Canada,
assignor to Plastic Packaging Products Limited, Mon-
treal, Quebec, Canada

Filed Nov. 27, 1964, Ser. No. 82,819

Term of patent 14 years

(Cl. D58—13)

FIG. 1

FIGURE 1 is a top plan view of a compartmented packaging tray, showing my new design;

FIGURE 2 is a side elevational view;

FIGURE 3 is a bottom plan view;

FIGURE 4 is an elevational view; and

FIGURE 5 is a sectional view thereof taken along line 5-5 of FIG. 1.

The characteristic feature of my design resides in a double walled tray including raised arcuate members corrugated along the longer axis of the tray and spaced apart by depressed areas corrugated along the shorter axis of the tray the extent of the depressions and continuing into the side skirts, all as shown.

I claim:

The ornamental design for a compartmented packaging tray, as shown and described.
